CABLE ANCHORING DEVICE

Hobart S. Geer, Corona, N. Y., assignor to American Safety Device Co., New York, N. Y., a corporation of New York

Original application March 21, 1931, Serial No. 524,240. Divided and this application November 9, 1931, Serial No. 573,806

2 Claims. (Cl. 304—19)

This invention relates to cable anchoring devices, and has for its general object and purpose, to provide simple, easily applied and highly efficient means for securely anchoring the ends of cables in relation to a fixed member, being more particularly intended and designed for use in anchoring the upper ends of scaffold suspending cables to a beam or other rigidly fixed element.

It is a more particular object of the present invention to provide an anchoring device of the above character embodying an arm to which the ends of the cables are suitably attached and relatively adjustable means for quickly and rigidly fastening or securing one end of said arm in superimposed position upon a supporting beam.

It is also an additional object of the invention to provide a cable supporting arm consisting of spaced parallel channel bars and a spacer member rigidly fixed between said bars at one of their ends, and having a lug or extension to engage under one edge of the beam flange together with a complementary locking lug engageable under the other edge of the beam flange, and means for rigidly fixing the latter lug in a longitudinally adjusted position upon said bars.

A further object of the invention is to provide an effective bracing strut for the cable suspending arm extending diagonally downward therefrom, and having a pivotally mounted shoe for bearing engagement against the lower or bottom flange of the supporting beam.

The subject matter of this application constitutes a division of my prior application for patent, Serial No. 524,240, filed March 21, 1931.

With the foregoing and other objects in view, the invention consists in the improved cable anchoring device, and in the form, construction and relative arrangement of its several parts, as will be hereinafter more particularly described, illustrated in the accompanying drawing, and subsequently incorporated in the subjoined claims.

In the drawing wherein I have disclosed one simple and practical embodiment of the invention, and in which similar reference characters designate corresponding parts throughout the several views,—

Figure 1 is a side elevation showing one embodiment of my improved cable anchoring means as applied to one of the beams of a building structure;

Fig. 2 is a transverse sectional view on an enlarged scale taken on the line 2—2 of Fig. 1; and

Fig. 3 is a horizontal sectional view taken on the line 3—3 of Fig. 1.

In the accompanying drawing, for the pur-

poses of illustration, I have shown the device as applied to an I-beam B which may constitute a permanent part of a building frame structure, or may consist of a separate element temporarily bolted or otherwise fixed to spaced parts of the building frame. The improved cable anchoring means as herein shown embodies an arm which is adapted to be secured to the beam B to project horizontally therefrom and outwardly beyond the face of the building wall. This arm consists of two channel bars indicated at 5 of the requisite length and weight. These bars are disposed in spaced parallel relation to each other with their channels opening outwardly on the opposite sides of the arm. A spacer member 6 indicated at 6 extends between these bars 5 at one of their ends and is bolted, riveted or otherwise securely and permanently fixed thereto as indicated at 7. Beyond the ends of the bars 5, this member 6 is formed with a downwardly and inwardly projecting lug 8, which extends beneath the bars 5, and is adapted for interlocking engagement under one edge of the top flange b of the I-beam B. A transversely extending plate 9 extends across the under sides of the bars 5, and is provided with a lug 10 on one end for interlocking engagement under the opposite edge of the top flange b of the I-beam. The plate 9 at its opposite edges is formed with the upwardly projecting lips 11, engaging the edges of the lower flanges on bars 5, and is centrally formed with a suitable opening to receive the bolt 12 which extends upwardly between the bars 5 and through a similar opening in the plate 13 extending across the top flanges of said bars. The opposite ends of this plate are provided with the downwardly projecting lips 14 engaging the edges of said flanges. The upper end of bolt 12 is threaded to receive the clamping nut 15. It will be obvious from this description that by loosening nut 15, plate 9 may be readily adjusted longitudinally of the bars 5 and its lug 10 properly engaged beneath the beam flange. Upon then tightening the nut 15, the plate 9 will be securely fixed in its adjusted position. In this manner, the end of the arm may be easily and quickly secured in laterally projecting relation to the top flange of the beam B and against longitudinal shifting movement relative thereto.

I also provide the bracing strut 16 in the form of a metal bar having longitudinally spaced openings 17 in one end portion thereof, which is adapted to extend upwardly between the spaced bars 5, the transverse bolt 18 having the nut 19 threaded on one end thereof being inserted 110.

through one of the openings 17 and coinciding with openings in the vertical webs of the bars 5. To the other end of this bracing strut, the angular plate or shoe 20 is pivotally secured by the bolt 21. As clearly seen in Fig. 1 of the drawing, one flange of the shoe is adapted to bear against one side of the vertical web of the beam B, while the other flange of said shoe bears against the upper surface of the lower or bottom flange b of said beam, so that the bars 5 will be securely braced against downward strain or stress.

In the present instance, I have shown the spaced suspending cables 22 provided upon their upper ends with suitable eye members 23 which are positioned between the spaced bars 5 to receive the transverse bolts 24 positioned through registering openings in said bars, and having suitable nuts 25 threaded upon one of their ends whereby the cables may be readily detached. If desired, the other ends of the spaced channel bars may also be connected by the transverse tie bolt indicated at 26.

From the foregoing description taken in connection with the accompanying drawing, the construction of my cable anchoring means and the several advantages thereof, in practical use, will be readily understood. It will be evident that by means of such a device, cables such as are commonly used for suspending scaffolds and other analogous purposes may be easily and quickly anchored to the beam or other fixed supporting part, and that the outwardly projecting arm to which the cables are attached is strongly braced and sustained against severe loads or stresses, thus obviating possible loosening or failure of the adjustable means for rigidly clamping the arm to the top flange of the beam.

I have herein shown and described an embodiment of the invention, which I believe to be very practical and serviceable for the purpose in view. It is nevertheless to be understood that

the invention as herein disclosed is susceptible of embodiment in various other alternative structural forms, and I therefore reserve the privilege of resorting to all such legitimate changes therein as may be fully embodied within the spirit and scope of the invention.

I claim:

1. In combination with a fixed member having vertically spaced flanges, a cable suspending arm, and means for detachably mounting said arm at one end thereof in superimposed position on said member, said means including relatively adjustable parts carried by said arm for interlocking engagement with opposite edges of the upper flange of said member, a strut, means for adjustably connecting said strut at one of its ends to said arm, and an angular bearing shoe pivoted to the other end of said strut and removably engaged with the vertical web and lower flange of said member.

2. A cable anchoring device for detachable mounting upon an eye-beam and the like, comprising a cable suspending arm, adjustable clamping means carried on one end of the arm for interlocking engagement over the upper flange of the eye-beam for securing the inner end of the cable-suspending arm thereto, cable connecting devices spaced lengthwise along the intermediate and outer portions of said arm for receiving cables for scaffolds and the like, a strut having a foot piece at its lower end adapted to engage against the web and lower flange of the eye-beam and extending upwardly and outwardly therefrom, and adjustable connecting means disposed between the arm and the upper end portion of the strut and located between said cable connections for supporting the arm with the suspension weight at opposite sides of the connection of the strut with the arm.
